SAMUEL P. WYRFEL, OF HARTFORD, CONNECTICUT, ASSIGNOR TO THE ARROW ELECTRIC COMPANY, OF HARTFORD, CONNECTICUT, A CORPORATION OF CONNECTICUT.

GUARD FOR FOOT PRESSES.

Application filed March 26, 1925. Serial No. 18,614.

My invention relates to guards for foot presses, and the object of my invention is to provide a guard which is not only certain of operation, but also readily applied to presses 5 of standard construction.

In the accompanying drawings—

Fig. 1 is a side elevation of a foot press to which is applied a guard in which my invention is embodied in one form; 10 Fig. 2 is a similar view showing the parts in another position; and

Fig. 3 is a front elevation of the press in the position shown in Fig. 1.

The press illustrated is of conventional 15 type, with work table 15, supported by legs 16, press base 17 on the table and standard 18 rising from the base. Pivoted at 19 in the standard is the foot-operated lever 20 which, as it swings backward, depresses the 20 vertically reciprocating tool carrier 21 guided in the standard. The tool 22 operates on the blank 23 (Fig. 2) positioned by the operative's hand 24 on the anvil 25 arranged on the base 17 below the tool 22.

The guard mechanism to which my invention relates, comprises a yoke 26, the legs of 25 which straddle the tool 22 and anvil 25 and embrace the standard 18 to which they are pivoted at 27. A shield 28 pivoted at 29 to 30 the yoke legs adjacent the head of the yoke, is connected adjacent its upper margin by link rod 30 to a pivot pin 31 on the standard and is thus caused to swing toward the tool 22 as the yoke 26 descends with the tool toward the base 17. This inward swing of the 35 shield 28 brings its upper margin sufficiently close to the tool carrier 21 to prevent the insertion of the operator's fingers above the shield into the space between the tool 22 and the anvil 25 as the tool descends. The set screw 40 32 by which the tool 22 is secured in the slide 21 is accommodated by the notch 33 (Fig. 3) in the shield as the tool descends.

The swing of the guard with tool slide 21 45 is effected by an adjustable lost motion connection between these parts. For this purpose I have shown a bracket 34 and brace 35 both bolted to the slide and supporting a rod 36 threaded at its upper end to receive nuts 50 by which it is adjustably attached to the eye 37 on the bracket 34. At its lower end the rod passes through a pivoted stud 38 on the yoke 26 and is provided with a head 39 which underlies the stud. Between the 55 bracket 34 and the stud 38 is confined under

slight stress a coil spring 40. It is thus obvious that while a positive lifting connection between the slide 21 and the yoke 26 is afforded by the headed rod 36, the downward thrust connection is not positive, but yielding through the spring 40.

Inasmuch as the downward movement of the guard with the tool slide is not positive, some means should be provided to prevent the tool 22 from approaching the anvil 25 if 60 the guard is not in obstructing position—as for example when the operator attempts to hold the work on the anvil as the tool descends. For this purpose I have shown a positive, adjustable link connection at 41 between the yoke 26 and a rocking stop lever 42 pivoted at 43 on a bracket 44 beneath the table 15. Riveted to the opposite end of the lever is a stop plate 45 with projecting tail 46. Secured at a suitable point on the foot 65 lever 20 is a cooperating stop pin 47. As the lever 20 swings backward on its pivot 19, to depress the tool slide 21, the guard 26 descends. If it is arrested, however, as indicated in Fig. 2, by the hand 24 of the operator, the link 41 halts the stop lever 42 in such position that the forward margin of the stop plate 45 lies in the path of the stop pin 47, with the result that the full stroke of the foot lever is halted before the tool 22 is 70 brought sufficiently close to the anvil 25 to injure the operator's fingers. If the latter are withdrawn, so that the guard now moves down under the influence of the spring 40, the lever swings the stop plate 45 out of 75 obstructing position and the foot lever 20 may continue its operating stroke. As it moves backward, the stop 47 then passes beneath the tail 46 of the stop plate 45 (Fig. 1, dotted lines) and prevents the operator from 80 lifting the guard, after the stop plate 45 is cleared by the stop pin 47, to again insert the fingers. The device is thus rendered fool 85 proof.

The guard mechanism is simple, effective, 90 and readily applied, with slight variations, to foot presses of different makes. The construction illustrated has been used with satisfactory results, but modifications will readily occur to those dealing with this problem, 95 which do not depart from what I claim as my invention.

I claim—

1. In a machine of the character described, 100 a vertically reciprocating tool, a fixed bed 105

with which it cooperates, a lever for operating the tool, in combination with a pivoted guard having a lost motion connection with the tool for movement therewith in both directions, a stop member on the tool-operating lever, and a cooperating stop member positively connected to the guard and moved out of obstructing position to permit completion of the working stroke of the lever only when the guard assumes protective position.

2. In a machine of the character described, a vertically reciprocating tool, a fixed bed with which it cooperates, a lever 15 for operating the tool, in combination with a pivoted guard directly connected with resilient lost motion to the tool for movement therewith in both directions, a stop member on the tool-operating lever, and a cooperating stop member positively connected to the guard and moved out of obstructing position to permit completion of the working stroke of the lever only when the guard assumes protective position.

25. 3. In a machine of the character described, a vertically reciprocating tool, a fixed bed with which it cooperates, a lever for operating the tool, in combination with a pivoted guard directly connected with the tool for movement therewith in both directions, a stop member on the tool-operating lever, and a cooperating stop member positively connected to the guard and moved out of obstructing position to permit completion of the working stroke of the lever only when the guard assumes protective position, said stop members cooperating to prevent lifting of the guard to non-protective position after the lever is freed to complete 40 its working stroke.

4. In a foot press, a standard, a tool carrier reciprocating therein, a fixed bed plate

above which the tool carrier works, a finger guard pivoted on the standard, operating means directly connecting the tool carrier to the guard for swinging the latter with the tool, a pivoted operating lever for reciprocating the tool carrier, a rocking stop lever, a positive connection between the latter and the guard, and cooperating stop elements on the stop lever and operating lever so related that in non-protective position of the guard the operating lever is restrained from a complete working stroke, while the guard when in protective position, is restrained from displacement therefrom as the operating lever completes its working stroke.

5. In a foot press, a standard, a tool carrier reciprocating therein, a fixed bed plate above which the tool carrier works, a finger guard pivoted on the standard, a bracket secured directly to the tool carrier, an operating connection between said bracket and pivoted guard for causing the latter to follow the vertical reciprocation of the tool carrier, a pivoted lever for reciprocating the tool carrier, a rocking stop lever, a positive connection between the latter and the guard, and cooperating stop elements on the stop lever and operating lever, such stop elements comprising a stop lug rigid with the operating lever and a stop member at one end of the rocking stop lever, said stop member having a shoulder which lies in the path of the stop lug on the operating lever only when the guard is in non-protecting position, said stop member having an extension or tail overlying the stop lug on the operating lever and serving to prevent lifting of the guard to non-safety position after said lug has passed the stop shoulder.

In testimony whereof I have signed my name to this specification.

SAMUEL P. WYRFEL.
